CARTON FOR PACKAGING SUIT GARMENTS
Harry Field, 5942 N. St. Louis Ave., and Joe Field,
6336 N. Oakley Ave., both of Chicago, Ill.
Filed Nov. 3, 1955, Ser. No. 544,774
3 Claims. (Cl. 206—7)

The present invention relates to double-faced corrugated cardboard packing boxes with built-in garment hanger rod such as used to contain multiple garment shipments, as between a manufacturer or distributor and retail merchandisers.

This invention is an improvement upon our application Ser. No. 488,532, filed February 16, 1955.

Whereas, our earlier filed application discloses a garment shipping container comprised of an interior or liner component having a sidewise access door panel which may be swung on a vertical axis to permit loading of the garments thereinto, together with an exterior encasing component which is made of uppermost and lowermost independent sections that meet at an intermediate level, the present invention contemplates an improved garment packaging article in which the characteristics of the lower exterior encasing component are merged with those of the interior liner component, and as a consequence of which there are achieved additional strength and utility advantages, as will be hereinafter pointed out.

In our improved packaging carton we have devised an interior component possessing all of the advantages inherent in our invention disclosed in the above referred to co-pending application, which include an uppermost perimetric infolded flange for receiving and stabilizing a space filling element designed to retain against dislodgement a series of hanger-supported garments in their suspensory condition even though the carton should become upset, inverted, or be made to undergo various other kinds of rough handling. The improved interior liner element of our packaging carton includes the advantages of a side door access as well as those of supporting a metallic hanger rod or beam and being in turn braced and reinforced by said beam. In addition, the interior liner member is reinforced by infolded closure flaps at its bottom affording stability to the sidewalls for enabling them to sustain the load transmitted through the hanger bar or beam in a vertical direction, particularly during the time that the garments are being placed thereinto with the hanger hooks suspended over the supporting beam.

By thus combining the characteristics of the outer component bottom section, including the overlapping closure flaps, with the heretofore known interior component sidewall elements, there are accomplished not only the economies of simpler setting up operations and reduction in the number of parts, but also those of added strength through bracing of the interior side wall bottoms.

With the improved features and advantages of our new design the need for anchoring by side bolstering support of the liner walls is no longer present, so that the required caution and responsibility impressed upon the packing clerk is thereby alleviated.

A primary object of the present invention, therefore, is to provide an economically constructible garment package for containing shipments of hanger-supported garments which may be loaded from a sidewise access door panel without depending upon achieving compactness of the garment load at the regions adjacent the liner sidewalls to prevent buckling or collapse thereof.

Another object of the present invention is to provide in such an improved garment packaging carton an interior or liner component which possesses the characteristics of an outer carton base structure whereby upon the erection and completion of the interior component into its load re-

2

ceiving condition, there is required no more effort, skill, or time than heretofore required to erect an article of this class in which an additional component had to be erected to supplement the services and functions of the liner.

5 Yet another object of the present invention is to provide a garment packaging case embodying an interior liner component having an integral outer casing characteristic of endmost infolded flap panels, a metallic beam supporting infolded flange at its upper extremity, together with the sidewise access door panel which is a subdivisional area of one of its wall panels and which includes an overlapping flap for reinforcing its meeting juncture with said wall.

10 The foregoing and other objects and purposes of the invention will be better understood by referring to the following detailed description taken in conjunction with the accompanying drawings, in both of which like references designate corresponding parts throughout, and in which:

15 FIG. 1 is a perspective view with portions broken away of a garment packaging assembly having embodied therein various features of our invention;

20 FIG. 2 is a flat plan view of a single sheet of double-faced corrugated board profiled and indicated by dotted outline to designate its cut and fold lines;

25 FIG. 3 is a longitudinal side sectional view taken approximately on line 3—3 of FIG. 1;

FIG. 4 is a perspective view looking up from the bottom of a completed packing case built in accordance with the present invention;

30 FIG. 5 is an enlarged perspective view of certain structural details pertaining to an improved hanger beam; and

FIG. 6 is another enlarged detail perspective view of a modified form of improved hanger beam.

35 In the accompanying drawings the reference numeral 11 indicates generally the outer component of our improved packing case, and the reference numeral 12 generally the inner component thereof. The outer component thereof 11 consists of a rectangularly foldable cublic having fold flaps 13 and 14 at the top and being open perimetrically as best indicated at 15, FIGS. 3 and 4, at the bottom. The dimensions of the outer component are preferably just enough larger than that of the inner component in all respects to effect a snug sliding fit encasement, as portrayed in FIG. 1. This is also true of the side walls 15, 16, 17 and 18, FIGS. 1 and 4, in respect to their encompassing the side panel walls 19, 21, 22 and the door panel wall 23a—23b of the inner compartment, see also FIG. 2.

40 As with our earlier embodiment, the two components are easily built up from flat storable double-faced cardboard sections, of which the inner component may resemble what is shown in FIG. 2, while the outer component may appear like a conventional carton in its knocked down condition. The user, who may be a clothing garment manufacturer or a distributor, in making up a shipment of garments for carrier transportation, will first erect the inner component by folding the top flange 27 over fold line 26, to form the continuous inward reinforcement and utility perimeter thereat doubled over the side walls 19—23a. Following this he will fold along lines 28, 29, 31 and 32, to form the rectangular inner member, or alternatively, the flat may be prefolded on line 29 with the subpanel 23b presecured to panel 19.

45 The end flaps 35, 36, 37 and 38 will next be folded over in opposed pairs and secured as by gluing or stapling, and at this point there is presented a rigid inner component that will stand steadily and be in condition to receive loading. At this time the metal hanger beam 49 may be installed by simply slipping its channel ends 49 down over the infolded flange portions 27 of walls 19

and 22, the double thickness of cardboard well filling the space of channel 49.

The component is now ready to be loaded, and this operation may be accomplished from the side access afforded by swinging the subpanel door 23a clockwise about fold line 31 as viewed in FIG. 1. Such loading convenience is of considerable importance to shippers of suit garments since it permits the packer to straighten out all lapels, drapes etc. by a simple hand stroke and what is even more important, to see that wrinkling is avoided. In contrast with containers which had to be loaded from the top, this also means the difference between receiving at the destination garments in readiness for sales display or having to restore the expected finish after unpacking.

It is also to be noted that the side and back walls of the inner component 19, 21, and 22, being integral with the folded flaps 35—38 will now be held erect and firm even under load stress without needing packing cargo support. This is of greater significance than contemplated because, as may be observed from FIG. 3, due to the shapes and arrangement of many types of garments, there often occur space voids at zones 43 and 44, just where needed to give sidewise support to the bottoms of walls independent of outer case characteristics.

The garment hanger supporting beam 41, see FIGS. 5 and 6, is a sheet metallic member which may be formed of channel stock cut to desirable lengths, and in the embodiment shown in FIG. 5, formed with outwardly bent securing flanges 47 and 48. For straddling the infolded flange area 27, there is preferred to be employed a sturdy U-shaped channel element 49 of heavier or tougher stock and of suitable length, to which the outwardly bent flanges 47 and 48 may be secured as at the outline 51 by spot-welding at one or more points such as designated 52.

In the embodiment shown in FIG. 6, the beam channel member 41 is cut off square, while the more rigid or sturdier flange straddling channel 49 is formed with outwardly extending struck-out tabs 53 which may then be welded at one or more points 54, to the side walls of the beam channel 41. By constructing the garment supporting beam 41 in this way, we are able to make the beam portion 41 of lightweight stock, while the portions 49 which have been known to suffer opening up under strain and shock, of heavier stock.

When all of the hanger supported garments are in position, with their hangers 55 arranged in alignment and their hanger hooks over the beam 41, then the packer will insert the space filling element 57, just as in our previous teaching, with the endmost panels thereof 58 tucked under the wall flanges 27. The sloping portions 59 will take the position shown in FIG. 3 resting against the angling shoulder parts of the garments. The packaging container is now in readiness for closure and sealing.

The door subpanel 23a is then swung back to the position in which it is shown in FIG. 1, and in this connection it will be observed that there is provided an edge flap 61 which is inserted behind inner component wall section 19, with the top portion of flap 61 wedged behind the doubled-over flange 27 thereat. This improvement has been found to contribute considerable bolstering reinforcement to the corner formed at the juncture between inner panels 23a and 23b with panel 19. Thereafter the outer component may be erected in conventional box art practice and slid down over the full length of the inner component and sealed if desired by applying a corner strip tape 63, FIG. 4, or otherwise.

While the present invention has been explained and described in contemplation of certain structural features, it is to be understood, nevertheless, that numerous changes and modifications are capable of being made without departing from its essential spirit and scope. According-

ly, no limitation is to be construed except as indicated in the hereinafter appended claims.

What we claim as our invention is:

1. A package case for a plurality of garments each on a shoulder hanger, said case including a closed bottom and four vertical walls together forming a vertical rectangular chute closed at the bottom and open at the top, the four walls constituting one continuous sheet of paper board folded to form front, rear and side walls, at least two opposite vertical walls having reinforcement means each comprising an inwardly extending inverted V-shaped fold of the paper board of said walls and each extending across the full widths thereof at the tops thereof and each fold being integral with the wall surface that it is reinforcing across substantially the full width of such wall surface, a stationary garment support and tie rod structure adapted to receive and hold a plurality of side by side garment sustaining hangers, said structure including a rod extending across the top of the case between said two opposite top reinforced vertical side walls and said structure resting on and being supported by the apices of said two folds and including portions each straddling one of the folds and holding the folded ends of the corresponding vertical walls in position, means forming a hinged openable and closable flap out of the top part of one of the vertical walls that is between the said two opposite vertical walls that sustain said garment-supporting rod to permit hinging of the flap to form an entrance door portion to the interior of the case, said door portion extending vertically from the top of the case for a major portion of the height of the case and terminating above the bottom of the case, the portion of said one wall below said door constituting a lower panel that is joined to opposite sides of the case at the bottom thereof, closure means for the open top and a member for holding garments on their hangers in the event of inversion of said packing case, said member comprising a sheet of corrugated board adapted for positioning overlying said rod and bent downwardly therefrom on opposite sides thereof to form sloping panels overlying the hangers, each sloping panel terminating in an upwardly bent wing adapted to be forced into position in the crotch of an inverted V-shaped fold at the top of an adjacent wall.
2. A package case for a plurality of garments each on a shoulder hanger, said case including a closed bottom and four vertical walls together forming a vertical rectangular chute closed at the bottom and open at the top, the four walls constituting one continuous sheet of paper board folded to form front, rear and side walls, at least two opposite vertical walls having reinforcement means each comprising an inverted V-shaped fold of the paper board of said walls and each extending across the full widths thereof at the tops thereof, a stationary garment support and tie rod structure adapted to receive and hold a plurality of side by side garment sustaining hangers, said structure including a rod extending across the top of the inside of the case between said two opposite top reinforced vertical side walls and said structure resting on and being supported by the apices of said two folds and including portions at opposite ends thereof each straddling one of the folds and frictionally engaging both the adjacent fold and the wall to which that fold is attached, whereby said structure braces said two opposite vertical paper board walls at said folds, means forming an openable and closable flap out of the top part of one of the vertical walls that is between the said two opposite vertical walls that sustain said garment supporting rod to permit hinging of the flap of that one vertical wall to form an entrance door portion to the interior of the case, said door portion extending vertically for a major portion of the height of the case, means movable to a position to close the open top of the case while the rest of the case which is loaded with garments suspended from said rod remains stationary, and means

within the case for holding garments on their hangers in the event of inversion of said packing case, said means being adapted to be positioned to extend above and across the hangers on opposite sides of the rod.

3. A package case for the plurality of garments each on a shoulder hanger, said case comprising a lower inner component and an upper outer component, the inner component including a closed bottom and four vertical walls together forming a vertical rectangular chute closed at the bottom and open at the top, the four walls constituting one continuous sheet of paper board folded to form front, rear and side walls, at least two opposite vertical walls having reenforcement means extending across the full widths thereof at the tops thereof, a stationary garment support rod adapted to receive and hold a plurality of side by side garment sustaining hangers, said rod extending across the top of the inner component between said two opposite top reinforced vertical side walls and supported by said two opposite vertical paper board walls at said reinforcements and being held against axial shifting and against shifting in a direction transversely of said two opposite walls, means forming an openable and closable flap out of the top part of one of the vertical walls that is between the said two opposite vertical walls that sustain said garment supporting rod to permit hinging of the flap of that one vertical wall to form an entrance door portion to the interior of the inner component, said door portion extending vertically for a major portion of the height of the inner component, whereby the case may be packed with garments on hangers by placing the garments into

10 15 20 25 30

the case through the open door and the packed case can be inspected through the open top thereof to determine proper positioning of the garments in the case at the side thereof opposite said door, the outer component also constituting paper board forming a closed top and four vertical walls forming a rectangular chute closed at the top and open at the bottom and making a sliding fit over the four vertical walls of the inner component so that it may be telescoped downwardly over the open top of the inner component to close the open top thereof while the inner component loaded with garments suspended from said rod remains stationary and supports the rod, the outer component extending over the inner component and constituting an endless band encircling the inner component and overlying substantially the entire door, thus restraining the inner component against outward bulging and means within the case for holding garments on their hangers in the event of inversion of said packing case, said means being adapted to be positioned to extend above and across the hangers on opposite sides of the rod.
